DOUBLE MULTICOLOR WEB PERFECTING ROTARY PRINTING PRESS

Filed April 16, 1930

UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

DOUBLE MULTICOLOR WEB PERFECTING ROTARY PRINTING PRESS

Application filed April 16, 1930. Serial No. 444,749.

This invention comprises a double multicolor web perfecting rotary printing press in which the first and second multicolor printing units are located in practically the same 5 horizontal and longitudinal vertical planes.

This invention further comprises a structure in which the plate cylinders of both printing units are disposed around the upper sides of their respective impression cylinders so that their corresponding inking mechanisms are subjected to the same temperature to facilitate the distribution and laying of the inks.

A practical embodiment of this invention 15 is represented in the accompanying drawings, in which

Fig. 1 represents diagrammatically a top plan view of the press with the inking mechanisms removed; and

Fig. 2 represents diagrammatically a side elevation of the press.

In the first multicolor printing unit of the press the impression cylinder is denoted by 1 and its plate cylinders by 2, 3, 4, 5, which plate cylinders are shown as arranged around the upper side of the impression cylinder. These plate cylinders are provided with inking mechanisms 6, 7, 8, 9, of any well known or approved form.

In the second multicolor printing unit of the press the impression cylinder is denoted by 10 and its plate cylinders by 11, 12, 13, 14, which plate cylinders are arranged around the upper side of the impression cylinder.

These plate cylinders are provided with inking mechanisms 15, 16, 17, 18, of any well known or approved form.

The two multicolor printing units are located in practically the same horizontal and longitudinal vertical planes.

The web 19 to be printed in multicolor on both sides passes from its supply roll, not shown, over a roll 20 and under rolls 21, 22, to and around the upper side of the impression cylinder 1 of the first multicolor printing unit under the plate cylinders 2, 3, 4, 5. From thence the web printed in multicolor on one side is fed under a roll 23 to and around the upper side of the impression cylinder 10 of the second printing unit under the plate

cylinders 11, 12, 13, and 14. From thence the web printed in multicolor on both sides is led around a roll 24 to a cutting mechanism, such, for instance, as a pair of coacting rotary cutters 25, 26.

An offset web 27 is shown as being fed from its supply roll 28 to and around the impression cylinder 10 of the second printing unit and from thence to its takeup roll 29.

The two printing units of the press may be driven from a common source of power, such, for instance, as an electric motor 30 which is herein shown as having a pulley and belt drive connection 31, 32, 33 with a cross shaft 34 connected through a train of gears 35, 36, 37, 38 with the impression cylinder 1 of the first printing unit and through the bevel gears 39, 40, longitudinal shaft 41, bevel gears 42, 43, cross shaft 44 and train of gears 45, 46, 47, 48 with the impression cylinder 70 10 of the second printing unit.

From the above description it will be seen that by placing the two printing units in the same horizontal plane and by locating the plate cylinders of the two printing units 75 around the upper sides of their respective impression cylinders, a number of advantageous results are obtained. This arrangement permits the use of two similar printing units with corresponding members in the 80 same horizontal plane. It also permits the corresponding inking mechanisms of the two printing units to be subjected to the same temperature to facilitate the distributing and laying of the inks. This arrangement also ensures a downward pressure at all times on the impression cylinder shaft bearings.

It is evident that various changes may be resorted to in the construction, form and arrangement of the several parts without departing from the spirit and scope of my invention, and hence I do not intend to be limited to the particular embodiment herein shown and described, but

What I claim is:—

1. In a multicolor web perfecting rotary printing press, first and second multicolor printing units located in practically the same horizontal and longitudinal vertical planes, the first printing unit being located beyond 100

the second printing unit, a cutting mechanism located in proximity to the second printing unit and means for feeding the web from the end of the machine where the cutting mechanism is located, past the second printing unit to the first printing unit, back to the second printing unit and from thence to the cutting mechanism.

2. In a double four color web perfecting 10 rotary printing press, first and second multi-color printing units located in practically the same horizontal and longitudinal vertical planes, the first printing unit being located beyond the second printing unit, each printing unit comprising an impression cylinder and four plate cylinders, the plate cylinders of both printing units being located on the same side of their respective impression cylinders, a cutting mechanism located in proximity to the second printing unit and means for feeding the web from the end of the machine where the cutting mechanism is located, past the second printing unit to the first printing unit, back to the second printing unit and from thence to the cutting mechanism.

In testimony, that I claim the foregoing as my invention, I have signed my name this 11th day of April, 1930.

HOWARD M. BARBER.
